COMBINED OXYGEN TENT FRAME AND GAS CONTROL UNIT

Frederick George Croasdale, London, England, assignor
to Oxygenaire (London) Limited, London, England, a
company of Great Britain

Filed Dec. 6, 1960, Ser. No. 63,127

Claims priority, application Great Britain June 8, 1960

Term of patent 14 years

(Cl. D83—1)

Des. 196,089

PAGE 2

FIG. 1 is a perspective view taken from the rear and one side of the combined oxygen tent frame and gas control unit embodying my new design;

FIG. 2 is a front elevational view thereof;

FIG. 3 is a side elevational view thereof showing the side opposite that shown in FIG. 1; and

FIG. 4 is a top plan view with portions thereof omitted for convenience of illustration only.

I claim:

The ornamental design for a combined oxygen tent frame and gas control unit, as shown.
